UNITED STATES PATENT OFFICE.

FREDERICK J. HARRISON AND WILLIAM J. KNOX, OF DUBOIS, PENNSYLVANIA.

BUMPER-BEAM, PILOT, AND COUPLING-POCKET CONSTRUCTION.

1,074,455.

Specification of Letters Patent. Patented Aug. 26, 1913.

Application filed January 16, 1913. Serial No. 742,425.

To all whom it may concern:

Be it known that we, FREDERICK J. HARRISON and WILLIAM J. KNOX, both citizens of the United States, residing at Dubois, in the county of Clearfield and State of Pennsylvania, have invented certain new and useful improvements in Bumper-Beam, Pilot, and Coupler-Pocket Constructions, of which the following is a specification.

10 The invention relates to a bumper beam construction for use in locomotive engines in conjunction with cooperating pilot and coupler pocket structures. The invention has for its primary objects; the provision of an improved bumper beam, pilot and coupler pocket construction so arranged that the pocket or pilot may be used interchangeably or together on the same beam; the provision of a structure of the character specified in which a very rigid and secure attachment between the beam and the pilot or pocket is secured, and which at the same time permits of a vertical adjustment of the pilot and pocket to suit different designs of locomotives wherein the distance of the beams from the tracks is not uniform; and in general the provision of a simplified construction of great strength, easily constructed and applied, and having a wide range 30 of use with different types of locomotives.

Certain embodiments of the invention are illustrated in the accompanying drawings, wherein—

Figures 1, 2, and 3, are plan, front elevation, and side elevation views respectively, of the bumper beam taken alone. Fig. 4 is an enlarged section on the line IV--IV of Fig. 2. Figs. 5, 6, and 7, are face, plan, and side elevation views respectively, of the 40 coupler pocket to be used with the bumper beam of Figs. 1, 2, and 3. Fig. 8 is a plan view of the bumper beam, with our improved pilot and coupler pocket applied thereto, the left hand half of the bumper beam being broken away. Fig. 9 is a front elevation of the structure of Fig. 8, with the left hand half of the bumper beam also broken away. Fig. 10 is an end elevation of the pilot, with the bumper beam in section, taken on the line X--X of Fig. 9. Fig. 11 is a section on the line XI--XI of Fig. 9.

Figs. 12 and 13 are plan and front elevation views respectively of a modified form of bumper beam, and Fig. 14 is an enlarged section on the line XIV--XIV of Fig. 13.

The bumper beam shown in Figs. 1, 2, 3, and 4 is preferably an integral cast member, and comprises a rectangular body portion 1 and a series of downwardly projecting brackets 2, 3, 4, and 5, such brackets being supported from the rear by means of the ribs 6, or in any other desired manner. These brackets 2, 3, 4, and 5 are designed to engage the rear face of the pilot to be later described, and above each bracket is a series of recesses or pockets 7 for engaging projections or teeth on the pilot so as to provide for the vertical adjustment of the pilot and to take the strain of supporting the weight of the pilot off the holding bolts, the end brackets 2 and 5 being provided with bolt holes 8, and the body 1 of the beam being provided with other bolt holes 9 and 10 (Fig. 4). At the center of the bumper beam is another series of recesses 11 adapted to receive teeth or projections on the rear side of the coupler pocket and provide for the vertical adjustment of such pocket. On each side of the recesses 11 are the bolt holes 12 for receiving the bolts for securing the pocket against the face of the beam.

The coupler pocket to be used with the bumper beam of Figs. 1, 2, and 3, is illustrated in Figs. 5, 6, and 7, such pocket consisting of a base or plate 13 and a socket portion 14. The rear face of the plate 13 is provided with the pair of projections or teeth 15 adapted to engage the recesses 11 at the center of the bumper beam, and adjacent the edges of the plate 13, the slots 16 are provided for the reception of the bolts for securing the pocket to the face of the beam. The pocket is shown in position upon the beam in Figs. 8 and 9 of the drawing, the socket being there shown as held in its lowest position of adjustment by means of the bolts 17. It will be seen that the pocket has a considerable range of vertical adjustment and that the engagement of the teeth 15 with the recesses 11 removes a considerable part of the holding strain from the bolts 17, and positively insures against

any slipping of the pocket due to loosening of the bolts.

Figs. 8, 9, 10, and 11 illustrate the pilot and its application to the bumper beam. The pilot is preferably made in one integral casting, and comprises a body portion 18 and a plurality of upwardly extending brackets 19, 20, 21, and 22, such brackets being provided with the slots 23 for the reception of securing bolts 24, which bolts also pass through the holes 9 and 10 in the body portion of the bumper beam 1 (Fig. 10). The end members of the frame of the pilot are also provided with other slots 25 located below the slots 23, which slots receive bolts 26 also passing through the holes 8 in the depending brackets 2 and 5 (Fig. 10). The rear faces of the brackets 19, 20, 21, and 22 are provided with the projections or teeth 27 adapted to engage the recesses 7 at the front of the bumper beam. This arrangement provides for the vertical adjustment of the pilot to suit varying conditions, the slots in the pilot permitting such adjustment. The engagement of the projections or teeth with the recesses serves to securely maintain the pilot against vertical or lateral movement, and removes the strain of supporting the pilot from the bolts. The use of the brackets 2, 3, 4, and 5 in connection with the brackets 19, 20, 21, and 22, serves to provide an extended bearing area between the beam and the pilot, thus affording a secure support for the pilot.

In Figs. 12, 13, and 14, a modified type of construction is illustrated, the bumper beam being in said construction made part of wood and part of metal, instead all of metal. The metal portions 28 and 29 of the beam fit around the wood member 30, the bolts extending through the holes 31 serving to maintain all three parts in fixed relation. The portion 28 is provided as in the other type of construction, with the downwardly projecting brackets 2', 3', 4', and 5' above which are the pockets or recesses 7' for receiving the projections upon the rear side of the pilot. The central portion of the beam is also provided with the series of recesses 11' for receiving the projections at the back of a coupler pocket. The upper edge of the metal portion 28 is provided with flanges 32 fitting over the top of the wood beam 30 and held in position by means of the bolts 33 (Fig. 12). Similarly the lower portion of the part 28 is provided with rearwardly extending flanges 34 opposite the brackets 2', 3', 4', and 5', and these brackets are secured by means of bolts 35 (Fig. 12) which extend vertically clear through the beam 30 and the bracket 34. The bolts 33 are also preferably extended clear through the beam 30 and the brackets 32 and 34.

Having thus described our invention and

illustrated its use, what we claim as new and desire to secure by Letters Patent, is the following:

1. In combination, a bumper beam comprising a body portion and bracket means projecting downwardly from said body portion and provided with a bearing surface, a pilot having a bearing face engaging the said bearing surface, interengaging projections and recesses on the bumper beam and pilot, and means for securing the said face against the surface. 75

2. In combination, a bumper beam comprising a body portion and a bracket projecting downwardly from said body portion, a pilot having its rear surface in engagement with the said bracket and the body portion above the bracket, securing means extending through the pilot and the bracket, other securing means extending through the pilot and the body of the beam, 80 slots being provided for the said securing means to permit of the vertical adjustment of the pilot, and the said pilot and beam having a plurality of interengaging recesses and projections whereby the pilot is supported against vertical movement independent of the said securing means. 85

3. In combination, a bumper beam comprising a metal body portion having at its central portion a series of engaging means 95 arranged one above the other vertically and adapted to engage a coupler pocket and provide for a vertical adjustment thereof, the said beam also having on either side of said series of engaging means other vertical 100 series of engaging means adapted to engage a pilot and permit of its vertical adjustment.

4. In combination, a bumper beam comprising a metal body portion having spaced along its front side a plurality of vertical 105 series of engaging means adapted to co-operate with other means on a pilot and prevent vertical and lateral movement thereof when the pilot is fitted against the front of the beam, the said means serving to provide a means for vertically adjusting the pilot. 110

5. In combination, a bumper beam of metal, and a pilot, the said beam and pilot having on their opposing surfaces co-operating recesses and projections for engaging such recesses, the said recesses being arranged in a plurality of vertical rows and the projections being similarly arranged in a plurality of vertical rows, whereby the 115 pilot may be adjusted vertically and held against lateral and vertical movement.

6. In combination, a bumper beam of metal, a pilot, and means for clamping the pilot to the beam, the said beam and pilot 120 having on their opposing surfaces co-operating recesses and projections for engaging such recesses, the said recesses being ar-

ranged in a plurality of vertical rows and the projections being similarly arranged in a plurality of vertical rows, whereby the pilot may be adjusted vertically and held 5 against lateral and vertical movement.

7. In combination, a bumper beam having a series of depending brackets with a series of engaging means extending upward on the beam above the brackets, and a pilot 10 having a plurality of engaging means on its rear side spaced so as to interengage with the other engaging means to permit a vertical adjustment of the pilot, and bolts for securing the pilot with its rear face in contact 15 with the beam and the said brackets.

8. In combination, a bumper beam having a series of depending brackets, and a pilot having a series of upwardly projecting vertically slotted brackets opposite the 20 brackets carried by the beam, bolts extending through the slots in the brackets for securing the pilot to the beam, vertical tooth

and recess means being provided on the opposing faces of the pilot and beam to permit of the vertical adjustment of the pilot 25 and to hold the pilot against vertical and lateral movement independent of the said bolts.

9. In combination, a cast bumper beam having its face provided at its central portion with a vertical series of holding means adapted to interlock with engaging means on a coupler pocket and provided adjacent the said series of holding means with bolt holes for receiving bolts extending through 35 the coupler pocket.

In testimony whereof we have hereunto signed our names in the presence of the two subscribed witnesses.

F. J. HARRISON.
WM. J. KNOX.
